(57) **CLAIM**

The ornamental design for tooth assembly for buckets, as shown and described.

DESCRIPTION

FIG. 1 is a front elevational view of tooth assembly for buckets in accordance with my new design;

FIG. 2 is a right-side elevational view thereof;

FIG. 3 is a left-side elevational view thereof;

FIG. 4 is a rear elevational view thereof;

FIG. 5 is a top plan view thereof;

FIG. 6 is a bottom plan view thereof;

FIG. 7 is a perspective view thereof;

FIG. 8 is a front elevational view of a first tooth of the tooth assembly for buckets shown in FIGS. 1-7, FIGS. 8-14 show the first tooth in the unassembled condition for ease of illustration;

FIG. 9 is a right-side elevational view thereof;

FIG. 10 is a left-side elevational view thereof;

FIG. 11 is a rear elevational view thereof;

FIG. 12 is a top plan view thereof;

FIG. 13 is a bottom plan view thereof;

FIG. 14 is a perspective view thereof;

FIG. 15 is a front elevational view of a second tooth of the tooth assembly for buckets shown in FIGS. 1-7, FIGS. 15-21 show the second tooth in the unassembled condition for ease of illustration;

FIG. 16 is a right-side elevational view thereof;

FIG. 17 is a left-side elevational view thereof;

FIG. 18 is a rear elevational view thereof;

FIG. 19 is a top plan view thereof;

FIG. 20 is a bottom plan view thereof; and,

FIG. 21 is a perspective view thereof.

The broken lines in the figures are for illustrative purposes only and form no part of the claimed design.
